UNITED STATES PATENT OFFICE.

FRANK H. VAN HOUTEN, JR., OF FISHKILL-ON-THE-HUDSON, NEW YORK.

DOUGH-DIVIDING MACHINE.

1,174,107.

Specification of Letters Patent.

Patented Mar. 7, 1916.

Application filed October 23, 1914. Serial No. 868,286.

To all whom it may concern:

Be it known that I, FRANK H. VAN HOUTEN, Jr., a citizen of the United States, residing at Fishkill-on-the-Hudson, in the 5 county of Dutchess and State of New York, have invented certain new and useful Improvements in Dough-Dividing Machines; and I do hereby declare the following to be a full, clear, and exact description of the 10 same, reference being had to the accompanying drawings, forming a part of this specification, and to the figures and characters of reference marked thereon.

This invention relates to that type of 15 dough dividing machines adapted for positive ejection of the divided portions of dough, the specific embodiment of the invention disclosed herein being particularly adapted for use in such machines as are 20 illustrated in prior Patent No. 788,123, and in co-pending application Serial No. 632,853, filed June 13, 1911, but it will be obvious that the invention is applicable to any machine of a type wherein movable measuring 25 pockets are employed with positively actuated pistons for ejecting the measured quantities of dough.

In the accompanying drawing, Figure 1 is 30 a longitudinal, horizontal section through the cylinder and connected parts of a machine embodying the features of the present invention, portions of the cylinder being seen in plan since the plane of the section is coincident with the meeting faces of the 35 cylinder sections. Fig. 2 is a front elevation thereof, a portion of the frame being seen in section. Fig. 3 is a cross section taken on the planes indicated by line 3—3 of Fig. 2. Fig. 4 is an end view of the parts 40 as seen in Fig. 2, the cylinder and frame being omitted. Fig. 5 is a detail end view of the threaded sleeve. Fig. 6 is a transverse, vertical section taken on the plane indicated by line 6—6 of Fig. 1 and looking 45 in the direction of the arrow.

Similar characters of reference in the several figures indicate the same parts.

The measuring cylinder 1 is provided 50 with tubular journals 2 and 3 rotatably mounted in the frame 4, the journal 3 being connected with the ratchet of pawl and ratchet mechanism 5 actuated by the sprocket 6 by driving means not shown, but such as is illustrated in my above-mentioned 55 prior patent, for imparting an intermittent rotary movement to the cylinder 1. Jour-

nal 2 is surrounded by sleeve bearing 2' carried by frame 4, and journal 3 is surrounded by a similar bearing 3'.

Cylinder 1 is provided with the measuring 60 pockets 7, 7 arranged at diametrically opposite sides of the cylinder and in any number proportioned to the capacity of the particular machine. An axial shaft 8 extends through the cylinder and is journaled in the ends thereof, and extends beyond the journal 2. Shaft 8 carries gear 65 wheels 9, 9, splined to the shaft within cylinder 1 and meshing with diametrically oppositely arranged sliding racks 10, 10, there 70 being a pair of such racks for each gear wheel 9, one rack being arranged relatively at one side of the longitudinal planes of shaft 8, and the other at the opposite side thereof for each gear 9, the inner end portions of the racks extending across said planes. From this position the racks are 75 adapted in operation to be moved longitudinally, with respect to themselves, by rotation of the gear wheels 9 inwardly in a 80 transverse-axial direction. Obviously, since movement of the gear wheels will shift the racks, shifting of the racks will rotate the gear wheels. To insure synchronism in the 85 movement of all the parts, these racks 10 which are above the gear wheels are connected by an axially extending bar 11, and the racks 10 below the gear wheels are connected by a similar bar.

Within each pocket 7 is arranged the 90 usual measuring and ejecting piston 12, each of said pistons having an inner terminal, preferably reduced, cylindrical shank 13 extending through a portion of the web of one of the bars 11, the said web being 95 formed with a bore or pocket 14 for the respective piston in which is arranged a plunger 15 whose inner end is adapted to enter a recess 16 in the shank 13. The plunger 15 is surrounded by a helical spring 100 17 engaging at one end an annular shoulder of the plunger and at the other end the base or terminal shoulder of the pocket 14, the spring being tensioned to maintain the inner 105 end of the plunger in recess 16. Each plunger 15 is provided with a head 18 for facilitating being grasped manually and drawn longitudinally away from shank 13 for releasing the same and allowing withdrawal 110 of the respective piston for enabling easy cleansing of the parts. The detachable engagement of the plungers 15 with pistons

12 while facilitating ease of application and removal of the pistons, insures, during use, unity of movement of the respective pistons with the racks 10.

A nut 19 is detachably secured to the journal 2, by screws or bolts 20, and is provided with threads intermeshing with the threads of a sleeve 21, the threads being of a very coarse pitch so as to serve as a cam for shifting the sleeve 21 longitudinally during relative rotation of the sleeve and nut. The sleeve 21 is keyed to shaft 8 so as the slide freely axially thereof while confined to rotate therewith. The laterally outstanding arms 22 are fixed to the outer end of sleeve 21 for co-operating with detents hereinafter described.

A yoke 23 is fixed to the frame 4 and has its arms inclosing a portion of the bearing 2', the outer end of the yoke being provided with a clamp bearing 24 engaging and adjustably retaining in position the tubular shaft 25 of a disk 26 and the said disk being arranged within the yoke and being provided with inwardly extending arms or horns 27 fixed to or formed integral with the inner face of disk 26. The arms 27 constitute the detents for arms 22 and are adapted, in operation, to interlock therewith for enabling relative rotation of shaft 8 independently of sleeve 21 as will hereinafter become more fully apparent. Axially slideable within the bore of shaft 25 is a sleeve 28 which is threaded onto a shaft 29 extending axially through the end of shaft 25 and being provided with a journal in shaft 25, the outer portion of shaft 29 being engaged by an operating wheel 30 for enabling manual rotation of shaft 29 whereby the sleeve 28 may be reciprocated axially. Oppositely disposed radial arms 31, 32 are fixed to the inner portion of the sleeve 28, and one of said arms is provided with an eye slidably surrounding and guided by pin 33 fixedly mounted in yoke 23. An indicator arm 34 is pivoted at its lower extremity on a pin 35 fixed on the respective side of yoke 23, the indicator arms extending from the pivot 35 to a position relative to a gradual scale 36 formed on a plate fixed to yoke 23 for indicating the relative distance of adjustment of the arm which of course is proportioned to the distance of adjustment of sleeve 28, and as sleeve 28 is in axial alignment with the threaded sleeve 21, the position of sleeve 28 is adapted to control the extent of axial movement of sleeve 21. A yoke or longitudinal slot is formed in the length of indicator arm 34 through which extends the outer terminus of arm 32 so that arm 34 is moved with sleeve 28 when the sleeve is adjusted for varying the extent of possible movement of sleeve 21, and the limits of movement of sleeve 21 with the resulting limit in capacity of the dough receiving

pockets are indicated by the position assumed by arm 34.

In operation, the parts being in the position indicated in Fig. 3, dough is forced into the pockets 7 at one side of the cylinder 1 by the usual plunger or other power means. The piston 12 of the pockets being filled are forced inwardly by the incoming dough and the movement of the piston effects the corresponding movement of racks 10 which revolve gears 9 and thus revolve shaft 8. As sleeve 21 revolves with shaft 8 and nut 19 remains stationary, the sleeve will be given an axial thrust which is sufficient for causing the arms 22 to assume a position in interlocking relation with arms 27 but spaced therefrom a distance sufficient for allowing a certain amount of rotary movement of sleeve 21 with cylinder 1 when the cylinder is again rotated. The axial thrust of sleeve 21 is effected by the threads of the sleeve and continues until the outer end of the sleeve strikes the inner end of sleeve 28 which latter sleeve is adapted for axial adjustment by operation of wheel 30 to any desired extent and such adjustment is indicated by the arm 34, the graduations 36 serving to indicate the result of the adjustment since the limit placed on the axial movement to sleeve 21 places a proportional limit on the possibility of inward movement of pistons 12. As soon as the pistons 12 reach the limit of their inward movement, the cylinder 1 is given a half revolution and during the first portion of such revolution the sleeve 21 rotates with nut 19, such rotation continuing until the arms 22 strike arms 27 and such rotation enabling the filled pockets 7 to move away from the point of supply and to a place of discharge. Immediately upon contact of arms 22 with arms 27, the sleeve 21 ceases to revolve with nut 19 and stops the rotation of shaft 8 while cylinder 1 continues to rotate. Thus, the racks 10 are caused to travel relative to the gears 9 which are of course held stationary by the shaft 8, and the travel of the racks 10 is such as to force the pistons 12 outwardly and thus to discharge the divided dough from the filled pockets. The reciprocation of the pistons in the empty pockets is a mere incident. The cylinder continues to revolve until the formerly empty pockets are brought into position for receiving a charge of dough and thereupon the operation is repeated. As the arms 22 by contacting with arms 27 retain sleeve 21 against revolving with nut 19, the said sleeve 21 during the rotation of cylinder 1, after contact of arms 22 with arms 27, is caused to travel axially inwardly by virtue of the threads of nut 19 acting on the threads of sleeve 21, and this axial travel of the sleeve continues until the arms 22 move inwardly

beyond the transverse axial plane of the inner extremity of arms 27 so as to leave the arms 22 free to revolve with sleeve 21 during the next pocket filling operation, the angular movement of the arms 22 during the outward thrust of sleeve 21 incident to the inward thrust of the pistons by the force of the incoming dough occurring between the arms 27 and terminating short of contact between arms 22 and arms 27, the space between said arms 22 and 27 being sufficient for enabling the requisite initial travel of the filled pockets before the beginning of the discharging operation of the pistons.

What I claim is:

1. In dough dividing mechanism, the combination with a rotary cylinder having a dough receiving pocket, of a rotary shaft 20 journaled axially in the cylinder and adapted to be rotated independently of the rotation of the cylinder, a piston in the pocket, gearing connecting the piston with the shaft for rotating the shaft independently of the cylinder and for imparting a thrust to the piston when the rotation of the shaft is interrupted and the cylinder continues to rotate, and means for interrupting rotation 25 of the shaft while the cylinder is rotating.

30 2. In dough dividing mechanism, the combination, with a rotary cylinder, having a dough receiving pocket, and a piston for discharging the dough therefrom, of a member, rotatable with the cylinder and shift-
35 able axially thereof, gearer with the piston for imparting a dough discharging thrust to the piston when said member is shifted axially, and means for interrupting rotary movement of the member and for effecting axial movement thereof.

3. In dough dividing mechanism, the combination, with a rotary cylinder having a dough receiving pocket, and a dough discharging piston therefor, of a member having a threaded connection with the cylinder and rotatable therewith, the threads being disposed to impart an axial movement to the member when the member is interrupted in its rotary movement during rotation of the cylinder, gearing connecting said member with the piston for imparting a dough discharging thrust to the piston when the member is shifted axially, and means for interrupting rotary movement of the member during rotation of the cylinder.

4. In dough dividing mechanism, the combination, with a cylinder having a dough receiving pocket and a dough discharging piston in the pocket, of a shaft journaled in the cylinder, gearing connecting the shaft with the piston for imparting a dough discharging thrust to the piston when the cylinder is rotated relatively to the shaft, a member connecting the shaft with the cylinder.

der and adapted to rotate with the cylinder and to leave the shaft free for rotation during rotation by the said member with the cylinder, means for interrupting rotation of the member during rotation of the cylinder for effecting relative rotation of the cylinder with respect to the shaft, and means for imparting an axial thrust to the member during such relative rotation for moving the member out of engagement with the interrupting means. 70 75

5. In dough dividing mechanism, the combination, with a cylinder having a dough receiving pocket and a dough discharging piston in the pocket, of a shaft journaled in the cylinder, gearing connecting the shaft with the piston for imparting a dough discharging thrust to the piston when the cylinder is rotated relatively to the shaft, a sleeve splined to the shaft and axially movable thereon, means for interrupting rotation of the sleeve during rotation of the cylinder for effecting relative rotation of the cylinder with respect to the shaft, and means for imparting an axial thrust to the sleeve for moving the same out of range of the interrupting means.

6. In dough dividing mechanism, the combination, with a cylinder having a dough receiving pocket and a dough discharging piston in the pocket, of a shaft journaled in the cylinder, gearing connecting the shaft with the piston for imparting a dough discharging thrust to the piston when the cylinder is rotated relatively to the shaft, a sleeve splined to the shaft and slidable axially thereof, the sleeve being formed with external threads, means for interrupting rotation of the sleeve with the cylinder for effecting relative rotation of the cylinder with respect to the shaft, and a nut fixed to the cylinder and having threads engaging the threads of the sleeve for imparting an axial thrust to the sleeve during such relative rotation for moving the sleeve out of range of the interrupting means.

7. In dough dividing mechanism, the combination, with a cylinder having a dough receiving pocket and a dough discharging piston in the pocket, of a shaft journaled in the cylinder, gearing connecting the shaft with the piston for imparting a dough receiving thrust to the piston when the cylinder is rotated relatively to the shaft, a member connecting the shaft with the cylinder and adapted to rotate with the cylinder and to leave the shaft free for rotation during rotation by the said member with the cylinder, an arm extending substantially radially from the said member, a detent disposed to at times lie in the path of movement of said arm with the said member during rotation of the cylinder for interrupting movement of the said member and shaft for causing the cylinder to rotate relative to the shaft, 125 125 125 125

and means for imparting a thrust to the member while held against rotation for moving the arm out of engagement with the detent.

- 5 8. In dough dividing mechanism, the combination, with a cylinder having a dough receiving pocket and a dough discharging piston for the pocket, of a shaft journaled in the cylinder, gearing connecting the shaft 70
10 with the piston for imparting a dough discharging thrust to the piston when the cylinder is rotated relatively to the shaft and for imparting rotation to the shaft relative to the cylinder when the piston is retracted by incoming dough, a member 75
15 engaging the shaft and fixed to rotate therewith while free for axial movement relative to the shaft, means for effecting an axial thrust of the said member when moved with
20 the shaft during retraction of the piston and for imparting an axial retraction of the said member during rotation of the cylinder relative to the shaft, and a stationary detent disposed in the path of a portion of said member 80
25 for interrupting rotation thereof during rotation of the cylinder.

9. In dough dividing mechanism, the combination, with a cylinder having a dough receiving pocket and a dough discharging piston for the pocket, of a shaft journaled in the cylinder, gearing connecting the shaft 95
30 with the piston for imparting a dough discharging thrust to the piston when the cylinder is rotated relatively to the shaft and for imparting rotation to the shaft relative to the cylinder when the piston is retracted by incoming dough, a member engaging the shaft and fixed to rotate therewith while free for axial movement relative to the shaft, means for effecting an axial thrust of the said member when moved with the shaft during retraction of the piston and for imparting an axial retraction of the said member during rotation of the cylinder relative to the shaft, and a stationary detent disposed in the path of a portion of said member 100
35 for interrupting rotation thereof during rotation of the cylinder, said member being axially movable out of engagement with said detent.
- 40 10. In dough dividing mechanism, the combination, with a cylinder having a dough receiving pocket and a dough discharging piston for the pocket, of a shaft journaled in the cylinder, gearing connecting the shaft with the piston for imparting a dough discharging thrust to the piston 110
45 when the cylinder is rotated relatively to the shaft and for imparting rotation to the shaft when the piston is shifted by incoming dough, a sleeve splined to the shaft and having a threaded connection with the cylinder for being moved axially during relative movement of the shaft and cylinder, an arm extending substantially radially from the sleeve, and an adjustable substantially fixed disk spaced axially from the sleeve 115
50 and having an axially extending detent projecting toward the arm of the sleeve and disposed for interrupting rotation of the sleeve with the cylinder, the axial movement of the sleeve being sufficient for moving the arm into and out of the transverse axial planes occupied by engaged portions of the detent.

- 55 11. In dough dividing mechanism, the combination, with a cylinder having a dough receiving pocket and a dough discharging piston for the pocket, of a shaft journaled in the cylinder, gearing connecting the shaft with the piston for imparting a dough discharging thrust to the piston 120
60 when the cylinder is rotated relatively to the shaft and for imparting rotation to the shaft relative to the cylinder when the piston is retracted by incoming dough, a member engaging the shaft and fixed to rotate therewith while free for axial movement

relative to the shaft, means for effecting an axial thrust of the said member when moved with the shaft during retraction of the piston and for imparting an axial retraction of the said member during rotation of the cylinder relative to the shaft, means in the path of axial movement of said member and adjustable axially thereof for interrupting movement of said member, and a detent in the path of rotation of a portion of said member for interrupting rotation thereof with the cylinder during a portion of the rotation of the cylinder, said member being axially movable out of engagement with said detent. 80

12. In a dough dividing mechanism, the combination, with a cylinder having a dough receiving pocket and a dough discharging piston for the pocket, of a shaft journaled in the cylinder, gearing connecting the shaft with the piston for imparting a dough discharging thrust to the piston when the cylinder is rotated relatively to the shaft and for imparting rotation to the shaft relative to the cylinder when the piston is retracted by incoming dough, a member engaging the shaft and fixed to rotate therewith while free for axial movement relative to the shaft, means for effecting an axial thrust of the said member when moved with the shaft during retraction of the piston and for imparting an axial retraction of the said member during rotation of the cylinder relative to the shaft, said member having a substantially radial arm, and a relatively fixed disk spaced from said member and having a detent extending at times in the path of rotation of the arm. 95

13. In dough dividing mechanism, the combination, with a cylinder having a dough receiving pocket and a dough discharging piston for the pocket, of a shaft journaled in the cylinder, gearing connecting the shaft with the piston for imparting a dough discharging thrust to the piston 110
14. In dough dividing mechanism, the combination, with a cylinder having a dough receiving pocket and a dough discharging piston for the pocket, of a shaft journaled in the cylinder, gearing connecting the shaft with the piston for imparting a dough discharging thrust to the piston 115
15. In dough dividing mechanism, the combination, with a cylinder having a dough receiving pocket and a dough discharging piston for the pocket, of a shaft journaled in the cylinder, gearing connecting the shaft with the piston for imparting a dough discharging thrust to the piston 120
16. In dough dividing mechanism, the combination, with a cylinder having a dough receiving pocket and a dough discharging piston for the pocket, of a shaft journaled in the cylinder, gearing connecting the shaft with the piston for imparting a dough discharging thrust to the piston 125
17. In dough dividing mechanism, the combination, with a cylinder having a dough receiving pocket and a dough discharging piston for the pocket, of a shaft journaled in the cylinder, gearing connecting the shaft with the piston for imparting a dough discharging thrust to the piston 130

dough receiving pocket and a dough discharging piston in the pocket, of a shaft journalized in the cylinder, gearing connecting the shaft with the piston for imparting 5 a dough discharging thrust to the piston when the cylinder is rotated relatively to the shaft and for imparting rotation to the shaft when the piston is shifted by incoming dough, a sleeve splined to the shaft and having a threaded connection with the cylinder for being moved axially during relative 10 movement of the shaft and cylinder, a detent for the sleeve for producing such relative movement, means adjustable axially toward and from the sleeve for limiting the extent of axial movement of the sleeve, and an indicator connected with said adjustable 15 limiting means for indicating the capacity of the pocket incident to the proportional amount of possible movement of the sleeve. 20 14. In dough dividing mechanism, the combination, with a cylinder having a dough receiving pocket and a dough discharging piston in the pocket, of a shaft journalized in the cylinder, gearing connecting the shaft with the piston for imparting 25 a dough discharging thrust to the piston

when the cylinder is rotated relatively to the shaft and for imparting rotation to the shaft when the piston is shifted by incoming 30 dough, a sleeve splined to the shaft and having a threaded connection with the cylinder for being moved axially during relative movement of the shaft and cylinder, an arm extending substantially radially from 35 the sleeve, an adjustable substantially fixed disk spaced axially from the sleeve and having an axially extending detent projecting toward the arm of the sleeve and disposed for interrupting rotation of the sleeve with 40 the cylinder, the axial movement of the sleeve being sufficient for moving the arm into and out of the transverse axial planes occupied by portions of the detent, a stop adjustable relative to the sleeve for controlling 45 the extent of axial movement thereof, a fixed pivot, an arm carried by said pivot and a connection between the stop and arm for swinging the arm on its pivot proportionally to adjustments of the stop.
